UNITED STATES PATENT OFFICE

2,121,422

ATTACHMENT OF FASTENINGS AND FITTINGS TO SUITCASES AND THE LIKE

Charles William Cheney, Soho, Birmingham,
EnglandApplication December 7, 1937, Serial No. 178,456
In Great Britain May 12, 1936

1. Claim. (Cl. 85—11)

The invention relates to the attachment of locks, fastenings and fittings to suit cases, bags, purses and the like, and distinctly to those in which the casing, or the part, to be attached is provided with integral self-penetrating clinchable prongs to be used for said attachment.

Such locks, fastenings and fittings have prongs of substantially V shape, additionally strengthened as, for example, in the manner described and illustrated in the specification of British Letters Patent No. 213,520 and for the attachment such a lock, fastening or fitting is placed prong-upwards in a cavity of a die of a press operative to force the material such as leather, cardboard or the like against the prongs to cause them to penetrate said material, and after which said prongs are effectively clinched down.

In locks, fastenings and fittings of this kind the invention provides an improved construction of attachment prong distinctive by one wing or blade of a V shaping being turned inwardly upon the other wing or blade, or by both wings or blades being turned inwardly towards each other, in manner providing in the prong double thickness metal substantially from base to point. The bases of one or both of the wings or blades merge into a boundary flange extending at right-angles, or substantially at right-angles, to the plane of the body of the casing or part of which the prongs are integral.

Particularly the invention provides for the formation of an attachment prong at a corner or angle, the one wing or blade of the V being closely closed inwardly onto the other wing or blade.

The invention is represented by the accompanying drawing applied to an attachment fitting for a carrier handle in Figs. 1-6, and to a back plate of a lock or similar casing in Figs. 7 and 8.

- 40 Fig. 1 is a side elevation.
- Fig. 2 is an end view of Fig. 1.
- Fig. 3 is an under-side plan of Figs. 1 and 2.
- Fig. 4 is an underside perspective view.
- Fig. 5 is a side elevation.
- 45 Fig. 6 is an underside plan of Fig. 5.
- Fig. 7 is an underside perspective view.
- Fig. 8 is a sectional elevation of Fig. 9 on the dotted lines.

Corresponding letters of reference are used in the drawing.

In Figs. 1-6 the attachment fitting is angular and in Figs. 1-3 at each corner is provided a prong *a* of V shape, comprising two wings or blades *c*, *d*, extending one each side the centre or axis *e* of the V and at right-angles to each other, these wings or blades projecting from a right-angled boundary flange *f* at their base to the point *g* of the V. This form of V shaping extending from the flange is in itself a very strong form of attachment prong, but one offering considerable resistance to penetration and disadvantageous for clinching. As clearly shown in Figs. 4-6 the wing or blade *c* is subsequently turned inwardly upon 10 the other wing or blade *d* without detrimental break or fracture of the metal at the base, so that the finished prong now presents from base to point substantially double thickness metal to further strengthen the prong, reduces its resistance to penetration, and makes it very suitable 15 for being inwardly clinched down after penetration.

The boundary flange *f* at the base of the prongs and from which they integrally project is a very 20 desirable form of the invention, in consequence of said flange extending where possible to both wings or blades.

The form of the invention Figs. 7 and 8 is exactly similar to Figs. 1-6 except that the carrier 25 for the prongs is a back plate *i* of a lock casing of a kind well known.

Nearly all metal locks, fastenings and fittings of the kind to which the invention relates can be readily provided with a set of penetrating 30 prongs constructed according to the invention.

Having now described my invention, what I claim and desire to secure by Letters Patent is:

In fastenings and fittings for suit cases, trunks, travelling bags and the like, a substantially flat 40 plate of rectangular shape, a boundary flange on said plate, and corner prongs, each comprising two substantially triangular wings integral with adjoining sides of said flange, respectively, and being folded upon one another to constitute 45 prongs of double thickness from point to base, the latter merging into said flange in a curve providing resistance against bending stresses.

CHARLES WILLIAM CHENEY.
